US0D1111822S

(12) **United States Design Patent** (10) Patent No.: **US D1,111,822 S**
(45) Date of Patent: ** Feb. 10, 2026

(54) **CONTAINER**

(71) Applicant: **Target Brands, Inc.**, Minneapolis, MN (US)

(72) Inventors: **Armonia Angelical Balch**, Minneapolis, MN (US); **Anna Maria Bofinger**, Shoreview, MN (US); **Nicholas A. Cyr**, Santa Clarita, CA (US); **Csaba Andrasfi**, Oakdale, MN (US); **Alyssa Rae Porubcan**, Plymouth, MN (US); **Suzanne Kathleen Strom**, Eagan, MN (US); **Jeanne N. Penn**, New York, NY (US)

(73) Assignee: **Target Brands, Inc.**, Minneapolis, MN (US)

(**) Term: **15 Years**

(21) Appl. No.: **29/928,791**

(22) Filed: **Feb. 15, 2024**

(51) LOC (15) Cl. **09-07**

(52) U.S. Cl.

USPC **D9/435**

(58) **Field of Classification Search**

USPC D7/392.1, 396.2, 629, 630; D9/434-436, D9/499

CPC A47G 19/00; B65D 51/00

(57) **CLAIM**

The ornamental design for a container as shown and described.

DESCRIPTION

FIG. 1 is a perspective view of a container showing our new design;

FIG. 2 is a front view thereof;

FIG. 3 is a back view thereof;

FIG. 4 is a right side view thereof, the left side view being identical;

FIG. 5 is a top view thereof; and,

FIG. 6 is a bottom view thereof.

The broken lines shown in the drawings are included for purposes of illustrating portions of the container and form no part of the claimed design.

1 Claim, 3 Drawing Sheets
